LUBRICATING DEVICE

John L. Creveling, near Tucson, Ariz., assignor to
 The Lubrication Corporation, South Bend,
 Ind., a corporation of Delaware

Application February 24, 1932, Serial No. 594,785

10 Claims. (Cl. 221—47.4)

This invention relates to lubricating devices. More particularly it relates to lubricating pumps of the type formed by operatively connecting permanent pump parts with a lubricant container, which may have been previously filled with lubricant (e. g. at the factory) for shipment and storage.

One of the objects of my invention is to provide lubricating pump parts capable of being associated with containers of lubricant and operated as lubricating pumps, in the assembly and use of which there is a minimum possibility of the operator soiling his hands or his clothes.

A further object of the invention is to provide lubricating pump parts that may be manufactured relatively cheaply.

A further object of the invention is to provide an efficient hand operated lubricating pump, having all the above described desirable characteristics and capable of producing relatively high pressures.

Further objects of the invention will be apparent after reading the subjoined description and claims and after viewing the accompanying drawings.

Prior hereto, hand lubricating pumps have usually been filled by scooping the lubricant from an open container and packing it in the reservoir portion of the lubricating pump with the hand or a paddle. In the devices described in this application, I propose pump parts which may be operatively associated with lubricant containers for the purpose of forming a complete pump. Moreover, the pump parts include a high pressure portion and also a substantially rigid low pressure cylinder which telescopes within the container and serves to support the sides of the container so that the container may be of relatively light construction. As the outside of the container is visible at all times, advertising matter and directions may be printed on the outside of the lubricant container where (inasmuch as such matter is upon an article which is to be thrown away after use) the same will not be objectionable to purchasers. The lubricant container can be easily telescoped over the cylinder and easily withdrawn, and in the assembly and use of the same there should be little excuse for a greasy or dirty exterior.

In general, the devices selected for illustrating my invention each comprise high pressure pump parts secured to a closure for the container, the closure having a supporting cylinder secured on the inner side thereof, the cylinder being telescopically associated within the container. A follower may be associated with the pump and adapted to contact with the lubricant in the container, for purposes described in a patent to Morris, Reissue 18123, or a piston actuated as by spring pressure may be employed.

In the accompanying drawings:

Fig. 1 is a view, partly in elevation and partly in section, showing a lubricating gun formed by pump parts associated with a lubricant-container;

Fig. 2 is a view, similar to Fig. 1, of a modified form of a lubricating gun, similarly formed;

Fig. 3 is a view, similar to Fig. 1, with a still different form of lubricating pump;

Fig. 4 is a bottom view of the container which is secured to the pump parts shown in Fig. 3;

Fig. 5 is a view, similar to Fig. 1, of another lubricant pump;

Fig. 6 is a view, partly in elevation and partly in section, of another form of pump;

Fig. 7 is a view, partly in section and partly in elevation, of still another form of pump;

Fig. 8 is a view, partly in section and partly in elevation, of a still different form; and

Fig. 9 is a detailed sectional view of the pump of Fig. 6, showing a bayonet joint.

Referring in detail to Fig. 1 of the drawings, a container or can 11 is telescoped over a supporting cylinder 12, the latter having its outer end secured to a closure 13 which is adapted to close the open end of the container 11 as well as the outer end of the cylinder 12. The closure 13 is formed with inclined passages 14 and 15 which communicate at their inner ends with a conduit 16, which is shown as a tube secured as by screw threads in the closure 13, the conduit serving to withdraw lubricant from the cylinder 12. Surrounding the conduit 16 and, if desired, slidably mounted thereon for movement within the cylinder 12, is an annular follower 17 which is adapted to contact with the surface of the lubricant in the container 11 and the cylinder 12 and prevent air from piercing the lubricant. A stop may be provided at the inner end of the tube 16 to prevent removal of the piston or follower 17.

Secured to the outside of the closure 13 is a casing 18 into which lubricant passes from the conduit 16, by means of the passages 14 and 15. The casing 18 has a reduced extension 19, in which there is telescopically mounted a tubular plunger 21. The plunger 21 is provided with a bore 22 and may be, if desired, formed from an ordinary piece of iron pipe. Secured to the outside of the closure 13, as by screw threads, is a solid fixed plunger 23 which is aligned with the bore 22 and adapted to enter the bore as the tubular plunger 21 is telescoped within the casing 18, so that the reciprocation serves to pump lubricant through the tubular plunger. Interposed in a chamber 25, formed in the enlarged portion of the casing 18 between the closure 13 and the inner end of the tubular plunger 21, is a spring 24 which normally urges the plunger 21 into the forward position shown. A check valve is inserted in the tubular plunger 21, as at 26; a vent

may be formed in the closure 13, as indicated at 27; and a stop 28 is formed on the plunger 21. In loading and operating this form of lubricating pump, the cover is removed from the container 11 and the container is then telescoped over the cylinder 12, the lubricant thus being forced cleanly into the cylinder. Prior to the filling operation, the follower 17 is positioned adjacent to the open end of the cylinder 12 and, as 10 the lubricant is forced in, is itself forced toward the other end of the cylinder, thus eliminating air pockets. Then the pump is applied to the fitting to be lubricated, with the outer end of the tubular plunger 21 contacting with the fitting, 15 and pressure is exerted manually upon the container 11 and, through it, upon the cylinder 12. This causes the enlarged portion of the casing 18 to be telescoped over the tubular plunger 21, and the solid plunger 23 to move into the bore 22, and 20 to force lubricant from the bore past the check valve 26. On releasing the pressure exerted upon the container 11, the spring 24 returns the parts to the position shown in the figure, and the vacuum created in the bore 22 draws lubricant into 25 and through the conduit 16, passages 14 and 15, and chamber 25, to the bore 22. Subsequent reciprocation of the parts causes this lubricant to be forced, out under high pressure, past the check valve 26, into the fitting to be lubricated. As 30 lubricant is withdrawn from the cylinder 12, the follower 17 moves inwardly, maintaining constant contact with the lubricant, to prevent air from piercing the lubricant. In withdrawing the empty can, the suction formed thereby insures 35 that the follower is left at the open end of the cylinder 12.

In Fig. 2, a casing 31 is formed with a larger diameter than that of casing 18 of Fig. 1, but has a similar function; and a spring protecting casing, formed by an extension 32 thereof, has an in-turned portion 33 which cooperates with the shoulder or projection 34 on the tubular plunger 21, to limit the outward movement of the plunger. Secured within the enlarged portion 35, of the 40 casing 31, is a small cylinder 36 with a bore 42 having a closed end 37 and an open end 38. Intermediate said ends, the cylinder 36 is provided with a plurality of transverse openings, such as 39, by means of which lubricant may pass from the outer chamber 41, formed between the outside 45 wall of the cylinder 36 and the inside walls of the casing 31, into bore 42. The tubular plunger 21 telescopes within the cylinder 36 and cooperates therewith to form a pump, and a spring 43 is interposed between the outer end of the cylinder 36 and shoulder 34 to automatically return the parts to the normal position shown.

This pump is operated similarly to the one described above. Reciprocation of the plunger 21 within the cylinder 36 causes lubricant to be forced into the fitting to be lubricated. The reciprocation is accomplished by pushing upon the container 11 and allowing the return thereof by means of the spring 43. After the plunger 21, 60 enters the cylinder 36, lubricant is forced forward through the plunger 21 and past the check valve 26 in the outer end thereof. As the tubular plunger 21 withdraws from the cylinder 36, suction is created in the chamber 42 which, when 65 the ports 39 are uncovered, draws lubricant from the cylinder 12 through the conduit 16, the passages 14 and 15, the outer chamber 41, and the passages 39 into the chamber 42.

In Fig. 3, the bottom end of the container 11, 70 is provided with a closure 46 in which there are

formed a plurality of inwardly extending ridges, such as 47. Secured to the closure 13 is a small cylinder or tube 48 which corresponds, in design and function, to the cylinder 36 of Fig. 2. However, the cylinder 48 extends inwardly from the closure and has, at its inner end, a plug 49 formed with a central passage-way 51, normally closed by a check valve comprising a ball 52 and a spring 53. Telescopically mounted in the small cylinder 48 is a tubular plunger 54 (which is 10 similar in design and function to the plunger 21 of Fig. 1, but considerably longer), provided at its inner end with a valve, formed by a valve casing 55, threaded onto the inner end of said tubular plunger, a ball 56 within said valve casing, and a spring 57 normally maintaining the ball against its seat. The plunger 54 and cylinder 48 thus form a high pressure pump. The tubular plunger 54 is provided with a projection or shoulder 58, and interposed between the projection 58 and the outer end of the cylinder 48 is a spring 59 which serves to urge the tubular plunger 54 toward its normal outwardly extended position.

In the operation of the lubricating pump, pressure is applied to the bottom 46, to move the large cylinder 12 and the small cylinder 48 forwardly over the tubular plunger 54; and, thereafter, the container is released to allow the spring 59 to return the parts to the normal position shown. This reciprocation of the cylinder 48, relative to the tubular plunger 54, causes lubricant to be drawn in through the spaces between the ridges 47, past the ball check valve 51, 52, and 53, and into the interior of the cylinder 48, and thence forced past the ball check valve 55—56—57 into the hollow of the tubular plunger 54. Thence, the lubricant is forced from the hollow of the plunger 54 into the fitting to be lubricated.

In Fig. 5 is shown a container 11, within which is telescoped a cylinder 61, provided with a closure 63 having a forwardly extending, cylindrical, reduced portion 64 forming an extension similar to extension 32 of Fig. 2. Extending inwardly from the extension 64, and having its inner end adjacent to the bottom of the container 11, is a smaller cylinder or tube 65, formed with lateral ports 66 leading from the interior of the cylinder 61 to the interior of the tube 65. The inner end of the tube 65 is closed by means of a solid plug 67 which contacts with the bottom of container 11. Telescopically mounted within the tube 65 is a hollow plunger 54 which extends forwardly through the reduced portion 64 and forwardly therefrom.

Surrounding the tube 65 is a sleeve 68, formed at its bottom end with a plurality of slots, such as 69, through which the lubricant passes when the sleeve approaches the bottom of the container 11. The sleeve 68 is slidably mounted upon the tube 65 and has, surrounding it and slidably mounted on it, an annular follower 71 which corresponds in design and function to the follower 17 of the other figures, thus providing means to insure the withdrawal of substantially all of the lubricant from the container 11.

The reduced portion 64 of the casing is provided, at its front end, with an in-turned portion 72 which coacts with the projection 58, formed on the plunger 54, to limit the outward movement of the plunger 54, and the reduced portion 64, itself, forms a protecting casing for the spring 59.

The operation of this form of device differs 75

from that previously described only in that, as the tubular plunger is reciprocated and moves inwardly of the tube 65, lubricant is trapped in the inner end of the tube 65 and forced outwardly, through the tubular plunger 54, past a check valve (not shown, but in all respects similar to the valve 55, 56, 57 of Fig. 3) into the fitting to be lubricated. When the tubular plunger 54 moves forwardly, relatively to the tube 65, a vacuum is created in the inner end of the tube 65 which causes the lubricant to be drawn through the passages 66 into the interior of the tube 65, so as to be forced out through the tubular plunger 54 on the next stroke. As the lubricant is withdrawn from the cylinder 61, the sleeve 68, together with the follower 71, moves downwardly in the container, maintaining the follower 71 continually in contact with the lubricant, to prevent air from piercing the lubricant. When the sleeve 68 reaches its lowermost position, lubricant is drawn in through the slots 69, and then upwardly between the sleeve and the outside of the tube 65, and then through the ports 66. The follower 71 continues downwardly, along the sleeve 68, until it reaches the bottom of the cylinder 62; and, thus, it is possible (even though the ports 66 are positioned a substantial distance from the bottom of the container) to withdraw substantially all the lubricant from the container.

In Figs. 6 to 9, I have shown the closure 76 as formed with a plurality of sockets 77 for cooperating with lugs 78 provided on the container 11, to detachably secure the container to the closure by bayonet lock.

In the lubricant pump illustrated in Fig. 6, a small cylinder or tube 79 is secured to the inner side of the closure 76 of the assembly, and is provided with an inlet check valve 81 at the inner end thereof, adjacent to the bottom wall of the container, when in place over the cylinder 12. A conical compression spring 82 is disposed, concentric with and about the tube 79, between the piston 17 and the adjacent wall of the closure 76, to continually urge the piston rearwardly. The outer end of the plunger 54 is provided with a discharge nozzle 83.

The lubricant pump, illustrated in Fig. 6, operates similarly to the pump shown in Fig. 3, except that the spring 82 applies a slight positive pressure to the lubricant, inducing its passage through the check valve 81 when the plunger 54 is moved outwardly, as by the spring 59. The bayonet lock, comprising the parts 77 and 78, adequately serves as a quick detachable means for the container and the remaining parts of the pump assembly.

In Fig. 7, I have shown a lubricant pump, having parts similar to that in Fig. 6, and like reference numerals have been used to designate like parts. The pump includes an elongated cylinder 85, which is secured to the closure 76 by an externally threaded portion 84, and which extends to the rear end of the cylinder 12. Slots 89 are provided in the rear end wall of the cylinder 85 to admit lubricant from the container thereto. A tubular plunger 21 is slidably disposed within the cylinder 85, with its bore aligned with a stationary plunger 86, secured to the rearward end of the cylinder 85, by means of a spider 88. A compression spring 87 is disposed between the spider 88 and the inner end of the plunger 21, to urge the plunger outwardly.

The operation of this form of pump is similar

to that described in connection with Fig. 1, except that the space within which the cylinder 85 is disposed is within the container, thereby providing a compact structure.

In Fig. 8, I have shown a pump wherein a small cylinder or tube 91 is slidably mounted upon the tubular plunger 54, having a spring 96 for urging the plunger outwardly. The tube 91 has a plug, in its rearward end, provided with a bore 92 therethrough, of relatively small diameter, which is aligned with a conical projection 93 which may be formed in the end wall of the container 11, or may be welded or otherwise secured thereto. The projection 93 is adapted to be partially received within the bore 92, to prevent the passage of lubricant from the tube 91 into the container, when the tube is thrust rearwardly. Means for assisting the inherent friction in causing the tube 91 to move with the plunger 54 may be used, if desired, and, as shown, comprises a friction ring 97, of spring steel, which is disposed within a groove formed in the outer wall of the tube 91, adjacent to its forward end, a portion of the bottom wall of the groove being cut away to permit the spring to contact with the outer surface of the plunger 54. Where used with lubricant of reasonable viscosity, the spring 97 may be dispensed with, if desired, as during return movement the plunger will engage with the shoulder in the bore of the tube 91 to open the valve 92-93, and during the pressure stroke of the plunger 54, the entrapped lubricant, if of reasonable viscosity, will offer enough resistance to passage through the restricted opening 92, to cause the tube 91 to move with the plunger and thus cause the opening 92 to be closed by the projection 93. A follower 64 is slidably mounted upon the tube 91 and performs the same function as the follower 17, described in connection with the foregoing figures.

The operation of this pump is similar to that of the pump illustrated in Fig. 6, except that, in place of a check valve 81, the projection 93 and apertured plug at the end of the tube 91 form a valve which is opened by movement of the plunger 54 through force applied by the spring 96. Such force, when applied, causes a limited movement of the tube 91, in the direction of travel of the plunger, to separate the plug from the projection and thus permit lubricant to be drawn within the tube 91. During the rearward or pressure stroke of the plunger 54, the tube 91 is first moved rearwardly to cause the mouth of the bore 92 in the plug to be seated upon the projection 93, whereupon continued rearward movement of the plunger will result in the discharge of lubricant under relatively high pressure through the nozzle 83.

It may thus be seen that I have provided lubricating pump parts capable of being easily associated with a lubricant container in which the lubricant is packed at the factory and in which the lubricant is transported and stored, and capable of pumping out the lubricant under relatively high pressure. Provision is made for displaying advertising matter and directions in a visible position on the container which is to be subsequently discarded. The pump parts are relatively inexpensive to manufacture and furnish a support for a cheap container. My invention also makes it possible for the operator to disassemble the lubricating gun and refill it with a minimum of chance of coming in contact with the lubricant.

The lubricating devices or "guns" of Figs. 1, 2, 75

5, and 7 are described and claimed in my co-pending applications, Serial Nos. 706,591 and 706,593, respectively, both filed on January 15, 1934.

5 It is to be understood that the above described embodiments of my invention are for the purpose of illustration only and various changes may be made therein without departing from the spirit and scope of my invention.

10 I claim:

1. A lubricating device comprising, a container having one end formed with a ridge, a closure for the other end of said container, a cylinder telescoped within said container and secured to said

15 closure, a tube secured to said closure and extending rearwardly therefrom to contact with said ridge whereby spaces are provided on each side of the ridge through which lubricant may be drawn into said tube, a follower surrounding

20 said tube and mounted for sliding movement thereon, a check valve at the inner end of said tube, a tubular plunger telescoped within said tube extending forward from the front end thereof, a check valve normally closing the rear end

25 of said tubular plunger, a projection formed on said tubular plunger in advance of said tube, and a spring interposed between said projection and the forward end of said tube.

2. In a lubricating device, a container, a cylinder telescoped within said container and extending substantially from end to end thereof, a tube positioned in said container and opening at one end to the container, said tube being secured relative to said cylinder, a follower surrounding said tube, a spring bearing upon said follower, and a pump associated with said tube.

3. In a lubricating device, a lubricant container, a tubular plunger mounted for reciprocation in said container, a tube slidably mounted on said plunger, a follower piston surrounding said tube, and means for closing the rearward end of said tube when it is urged rearwardly by said tubular plunger.

4. In a lubricating device, a lubricant container, a tubular plunger mounted for reciprocation in said container, a tube slidably mounted on said plunger, friction means for causing said tube to follow said plunger and means for closing the rearward end of said tube when it is urged rear-

50 wardly by said plunger.

5. In a lubricating device, a lubricant container, a tubular plunger mounted for reciprocation in said container, a tube slidably mounted on said plunger, friction means for causing said tube to follow said plunger, means for closing the rearward end of said tube when it is urged rearwardly by said plunger and a lubricant follower piston surrounding said tube.

6. In a lubricating device, a lubricant container, a tubular plunger mounted for reciprocation in said container, a tube slidably mounted on said plunger, a spring for urging said plunger outwardly of said container, friction means for causing said tube to follow said plunger and means for closing the rearward end of said tube when it is urged rearwardly by said plunger.

7. A lubricating device of the removable and replaceable lubricant cartridge type comprising, in combination, a tubular casing having smooth cylindrical inner and outer side walls, said casing being open at one end and provided with a fixed end closure at its other end, a high pressure pump

cylinder located within said casing and disposed along the longitudinal axis thereof with its inlet end located adjacent to the open end of said casing, a tubular high pressure pump plunger mounted for reciprocation in said cylinder, said plunger having a discharge end extending through and outwardly of said casing end closure, a lubricant cartridge having a smooth cylindrical inner side wall telescoped over the outer side wall of said casing and in frictional engagement therewith to transfer the lubricant contents thereof into the casing and to provide a closure for the rearward end of the casing, means providing an inlet valve at the inlet end of said cylinder, and a follower piston slidably mounted on said pump cylinder and adapted to move rearwardly within the casing as lubricant is withdrawn therefrom into said pump cylinder.

8. A lubricating device of the removable and replaceable lubricant cartridge type comprising, in combination, a tubular casing having smooth cylindrical inner and outer side walls, said casing being open at one end and provided with a fixed end closure at its other end, a high pressure pump cylinder located within said casing and disposed along the longitudinal axis thereof with its inlet end located adjacent to the open end of said casing, a tubular high pressure pump plunger mounted for reciprocation in said cylinder, said plunger having a discharge end extending through and outwardly of said casing end closure, a lubricant cartridge having a smooth cylindrical inner side wall telescoped over the outer side wall of said casing and in frictional engagement therewith to transfer the lubricant contents thereof into the casing and to provide a closure for the rearward end of the casing, and a follower piston mounted concentric with said pump cylinder and adapted to move rearwardly within the casing as lubricant is withdrawn therefrom into said pump cylinder.

9. In a lubricating device, a quick detachable lubricant container, a cylinder telescoped within said container and in substantial frictional engagement therewith, said container providing a closure for one end of said cylinder, a closure member rigidly secured to the other end of said cylinder and providing a closure therefor, a tube secured to said member and positioned in said container and at one end extending approximately to the closure end of the container, means at said end of said tube to provide communication between said cylinder and tube, and a lubricant pump plunger reciprocably mounted in said tube.

10. In a lubricating device, a quick detachable lubricant container, a cylinder telescoped within said container and in substantial frictional engagement therewith, said container providing a closure for one end of said cylinder, a closure member rigidly secured to the other end of said cylinder and providing a closure therefor, a tube secured to said member and positioned in said container and at one end extending approximately to the closure end of the container, means at said end of said tube to provide communication between said cylinder and tube, a lubricant pump plunger reciprocably mounted in said tube, and means in said tube and on said plunger for limiting movements of said plunger.

JOHN L. CREVELING.
